UNITED STATES PATENT OFFICE.

WILLIAM M. SHRADER, OF BUCYRUS, OHIO, ASSIGNOR OF ONE-HALF TO
CHARLES L. BUCK, OF SAME PLACE.

DESIGN FOR A BRACKET.

SPECIFICATION forming part of Design No. 34,083, dated February 12, 1901.

Application filed January 18, 1901. Serial No. 43,814. Term of patent 14 years.

To all whom it may concern:

Be it known that I, WILLIAM M. SHRADER, a citizen of the United States, residing at Bucyrus, in the county of Crawford and State 5 of Ohio, have invented and produced a new and original Design for a Bracket, of which the following is a specification, reference being had to the accompanying drawing, forming part thereof.

10 The drawing represents a perspective view of a bracket embodying my design.

The design comprises the bracket *a*, having at the outer end of its horizontal arm a bowl or cup-like configuration *b*, from the center of which projects an upright member *c*.

15 The leading feature of the design is the

bracket with the cup-like configuration and the upright member projecting from the center thereof.

Having thus described my invention, what 20 I claim as new, and desire to secure by Letters Patent, is—

The design for a bracket, herein shown and described.

In testimony whereof I have signed my 25 name to this specification in the presence of two subscribing witnesses.

WILLIAM M. SHRADER.
